[57] ABSTRACT

An Apparatus for use with a reciprocating press for feeding pieces of leather into and from between the press elements. The pieces of leather are thus cut into desired shapes and ornamented by punching designs such as stitching marks and holes there through to provide portions of shoe tops, belts and other articles. The device for feeding such pieces of leather is an electrically heated, cutting die supporting carrier or vehicle which rides on a supporting guide plate with track elements thereon. The supporting plate is fixed to the stationary element of the press. The carrier or vehicle is supported on the guide plate by spring urged rollers which yield under pressure when the pieces of leather are being operated upon the press. The carrier is moved manually on the supporting guide plate from a loading and discharge position in front of the press to punching position within the press.

HEATED DIE CARRIER

My invention relates to an electrically heated die carrying vehicle or carriage for leather cutting and punching machines. At present various portions of shoes have ornamental markings thereon which are made in the leather by dies heated and pressed into or through said portions of the shoe leather prior to actual construction of the shoe itself. The dies also cut the leather into specifically shaped pieces. Such ornamental designs include circular or other shaped holes and closely shaped punchings to represent stitching. Other leather articles such as straps, pocketbooks, etc., are similarly processed. This involves placing the piece of leather on a specifically designed cutting die, mounting said die on a heavy electrically heated carriage and moving the heated carriage, die and leather into a press machine. After the pressing, cutting and punching operation has taken place, the heated carriage with the die and leather are removed from the press and the shaped and ornamented piece of leather removed from the die. Previously these cuttings and markings were accomplished by hand tools and stitching machines. My device performs such results with speed, accuracy, and efficiency with a great savings of time and labor.

Other objects and advantages of this invention will become apparent from the following description taken in connection with the accompanying drawings wherein are set forth by way of illustration and example certain embodiments of this invention.

FIG. 1. is front view of a pressing machine with the heated carriage therein.

FIG. 2. shows a perspective view of a guide plate.

FIG. 3. is a perspective view of the heated carriage.

FIG. 4. shows a thick aluminum block.

FIG. 5. includes the electrical system.

FIG. 6. illustrates a cutting die block.

FIG. 7 shows the steel undercarriage.

FIG. 8 illustrates an enlarged detail of the roller mounting on a plane through line 39 - 39 of FIG. 7.

A conventional pressing machine (1) is shown in FIG. 1 mounted on a table or standard (2). The press has a rectangular front opening (3) therein with a stationary base plate (4), a vertically reciprocating plunger (5) and conventional means not shown for operating said plunger. My invention includes an elongated rectangular steel guide plate (6), better shown in FIG. 2, with a flange (7) extending from its lower surface. The flange (7) is bolted as at (8) to the front edge of the stationary base plate (4) of the press, as shown in FIG. 1. The steel guide plate (6) extends over the entire stationary base plate (4) of the press (1) and extends outwardly from the opening (3) in the press. Adjacent the side edges of the top of the guide plate (6) are fixed two teflon guide strips (9), see FIG. 2, between which applicants heated carriage, FIG. 3, rides into and out of the opening (3) in the press.

The heated carriage (10) is best shown, as assembled, in FIG. 3 and includes a steel under carriage (11) including a substantially rectangular plate FIG. 7 (31) having top (32), bottom (33) and sides (34), said plate (31) having spring (36), FIG. 8, pressed retractable ball bearing rollers (12) extending below its lower corners through openings (35) in the plate (31). As mentioned on page 1 in lines 11 through 13, "The carrier or vehicle is supported on the guide plate by spring urged rollers which yield under pressure when pieces of leather are being operated upon in the press." The outer vertical surfaces (13) of the steel under carriage (11) make sliding contact with opposed sides of the teflon guides (9) on the guide plate (6) FIG. 2. To the rear and side portion of the top (32) of the steel plate (31) of the under carriages (11) there are mounted relatively thick fibre blocks (14) for heat insulation purposes.

A thick electrically heated aluminum rectangular block (15) is shown in Figure 4. This block (15) has a large scrap discharge opening (16) in its center portion and deep rounded slots (17) in its opposite sides extending from the front edge (18) of the block to a point (19) spaced from the rear edge (20). Electric heater elements (21), FIG. 6 are inserted in the

slots or grooves (17) from the front edge (18) of the block (15). Two positioning pins (22) extend upwardly from the top surface of the electrically heated block (15) to receive a leather cutting die plate (23) placed on top of the block (15).

- 5 The deep rounded slots (17) on the opposite sides of said block (15) are covered by side plates (24) which are screwed to block (15) to enclose the elongated tubular heater elements (21). As shown in FIG. 3 a handle member (25) having a wooden grasping element is attached to the side plates (24) adjacent to open ends of the slots (17) and extend a distance from said block (15). Between the side portions of the handle element (25) there is a heater control switch box (26) having a switch (31) and heater control element (32), see FIGS. 3 and 5 which is mounted upon an angle plate (27) attached to the block element (15) and extending above said heater control switch box (26) to insulate it from the heater block (15). Electrical connections interconnect the heater elements and the heater control switch box.

- 10 As assembled the heated carriage (10) includes the steel under carriage (11) having the spring pressed ball bearing rollers (12) and the insulating fibre blocks (14) attached to the upper side of the steel under carriage (11) and the aluminum block (15). The thick aluminum block (15) is fixedly attached through said fibre blocks (14) as by bolts not shown to the steel under carriage (11).

- 15 FIG. 6 shows an example of a cutting die plate (23) having various forms of cutting elements (28) projecting from the upper surface. Positioning pins (29) and openings (30) on the lower surface of the cutting die plate (23) serve to position and retain the cutting die plate on top of the heater block (15).

- 20 In operation the guide plate (6) is attached through flange (7) to the press base plate (4). The heater carriage assembly (10) is slidably placed upon the steel guide plate (6) between the teflon guides (9). The heating elements (21) are inserted in slots (17) and the electric switch 31 on switch box (26) is turned on to bring the aluminum block (15) and the cutting die (23) to the operating temperature. The cutting die (23) has been fitted to the top of the heater carriage (10) and a piece of leather is now placed on the top of the cutting die plate (23). The operator then moves the heater assembly (10) into the press opening (3) and the press plunger (5) is operated one complete stroke down and up. The heater assembly (10) is withdrawn from the press on its rollers (12) and the punched leather piece removed. This operation is manual but rapidly repeated on successive pieces of leather to cut and perforate the same.

- 25 The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and changes which come within the meaning and range of equivalency of the claims are therefore intended to be embraced therein.

30 What I claim and desire to be secured by United States Letters Patent is:

- 35 1. In combination with a press having a stationary base and a plunger, means for moving said plunger toward and from the stationary base, a heated die carrier comprising an under carriage, a block means, insulating means between the under carriage and the block means, electric heaters in said block means, a cutting die removably resting on top of said block means and means for moving said heated die carrier and cutting die between the stationary base and plunger of the press and retracting it therefrom.

- 40 2. The combination of claim 1, wherein the block means comprises a thick rectangular metallic block having a top, bottom, two long opposite sides and two opposite ends; means defining a scrap opening extending through the central portion of the block from top to bottom; means defining grooves in the two long opposite sides of the block extending from one end of said block; side elements and means for fixedly at-

taching the side elements to the long opposite sides of the block to cover said grooves and means on the top of said block for locating the cutting die.

3. The combination of claim 2, wherein the under carriage comprises a rectangular plate member having a top, bottom and sides, means defining openings, one adjacent each corner of said plate member, separate elements extending through said corner openings; resilient means supporting said elements for movement into and out of said corner openings, interconnecting means between said separate elements and the rectangular plate; heat insulating members; and means connecting the plate through said insulating members to the block means.

4. The combination as recited in claim 2 wherein there is an elongated guide plate for supporting the heated die carrier for movement from a position between the stationary base and plunger of said press to loading position spaced from the press, said guide plate having a flat upper surface with longitudinal side edges and a transverse flange on its lower surface, means fixedly connecting said flange to the stationary base of the press, guide means on the flat upper surface of the rectangular guide plate adjacent the longitudinal side edges, the heated die carrier movably resting between said guide means on said guide plate.

5. The combination as recited in claim 4 wherein the block means is heated by electric heaters comprising elongated tubular heater elements in the grooves of said block and having electrical connections extending outwardly from said block; handle members extending from the block and means attaching said handle members to the block; a heater control means connected with said handle members and means connecting said control means to said handle members; heat insulation means and means attaching said heat insulation means to said block, said heat insulation means extending between the block and the heater control means.

6. A heated die carrier comprising an under carriage; a rectangular block like member having a top, a bottom, long opposite sides and opposite ends; means defining a scrap opening through the central portion of the block from top to bottom; means defining slots in the long opposite sides of the block extending from one end of the block; side plates and means fixedly mounting said plates on the long opposite sides of the block to cover said slots; means on top of said block for retaining a cutting die in operating position; heat insulating means; means interconnecting the heat insulating means between the block means and the under carriage; heater means in said block means; said cutting die removably resting on said block means; means for controlling said heater means and handle means for moving said heated die carrier and cutting die.

7. A heated die carrier; an under carriage supporting said die carrier comprising a substantially rectangular rigid plate member having top, bottom and sides, means defining openings through said plate member, one adjacent each corner of said plate member; a supporting element extending through each of said openings; yieldable means supporting said elements for movement into and out of said corner openings; mounting means attaching said yieldable means to said plate and said elements; heat insulating members on top of said plate; and block means; heat insulating means; means interconnecting the heat insulating means between the block means and the under carriage; heater means in said block means; a cutting die removably resting on said block means; means for controlling said heater means and handle means for moving said heated die carrier and cutting die.

8. A heated die carrier comprising an under carriage; a block means; heat insulating means; means interconnecting the heat insulating means between the block means and the under carriage; heater means in said block means; elongated electric heater elements insertable in the slots in the sides of said block; electric wiring and means connecting said wiring to said heater elements; handle means and means attaching the handle means to the block; a heater control means; means connecting the heater control means to the wiring; means sup-

porting said heater control means; additional heat insulation means located between the block and heater control means supporting said heat insulation means on said block; a cutting die removably resting on said block means, said heated die carrier and cutting die being moved manually by said handle means.

9. The combination of a heated die carriage and a press; said press having a vertical front wall; means defining a rectangular opening in the vertical front wall of the press; a plunger inside said opening; means for vertically reciprocating the plunger inside said opening; a base plate within said opening in opposed relation to said plunger; said base plate having a front edge adjacent the lower edge of said opening; an elongated guide plate; means mounting the guide plate intermediate its ends to the front edge of the base plate, said guide plate extending over the base plate and outwardly through the opening in the press; guide strips; means mounting said strips adjacent the sides of the top surface of the elongated guide plate; a carriage resting on the guide plate between said guide strips and slidably contacting the guide strips for manual movement into and out of the opening of the press from a loading and discharge position outside the opening to a position in the press beneath the plunger of the press; the carriage includes a flat bottom substantially rectangular under carriage plate; ball bearing rollers; spring means for mounting said rollers in openings at each of the corners of said under carriage plate for urging said rollers downwardly into yielding rolling contact with the guide plate; heat insulating means of U form on the top of the under carriage plate; means fixedly attaching said insulating means to said under carriage plate; a thick aluminum block having a central scrap discharge opening through its central portion; means fixedly connecting said thick aluminum block to the U form insulating means with the discharge opening in the block in registry with the space between the arms of the U formed by the insulating means; two opposite side walls of the block being cut-away to provide slots closed at one end and open at the opposite end; side plates; means for attaching said side plates to the side walls of the block to cover said slots; handle means; attaching means connecting said handle means to the side plates; electric heater elements inserted in said slots; control and switch means; means connecting said control and switch means to the electric heater elements and to the handle means for easy accessibility; additional heat insulation means; means connecting said additional heat insulation means to said block to insulate the control switch means from the block; a die plate for cutting designs in leather located on top of the aluminum block and; interfitting connection means removably mounting the die plate on the top of the aluminum block; whereby a piece of leather to be cut and decorated by punching is placed on top of the die plate and the entire carriage manually moved under the press plunger; the press plunger operated for one down and up stroke and the carriage moved out from under the plunger discharged and re-loaded.
